MECHANICAL TRIP CONTROL FOR PRESSES

Vasil Georgeff, Chicago, Ill., assignor to Danly
Machine Specialties, Inc., Chicago, Ill., a cor-
poration of Illinois

Application November 3, 1947, Serial No. 783,748

5 Claims. (Cl. 192—138)

1

My invention relates to a mechanical trip control for presses and more particularly, to an improved mechanical control for power presses, enabling single stroke, continuous and inching operations of a power press through a completely mechanical control system.

In the operation of power presses it is necessary to control the press to permit it to go through a single cycle once upon the actuation of the control in order to permit the finished work to be removed and a new blank to be inserted. In some operations, it is desirable that the press run continuously, there being sufficient time to feed a strip of stock between the actual work performing steps. Then, too, in removing and inserting dies or in adjusting dies, a control must be able to "inch" and stop it at any desired part of its cycle. Most of the controls for presses involve the use of electrical systems, comprising a plurality of relays and complicated electrical wiring. These systems are not only expensive but are susceptible to frequent breakdowns resulting from short circuits or deterioration of the contact parts of the relays. Their complicated nature is such that when trouble develops it is a time consuming task, first to locate the trouble, and frequently in its repair.

One object of my invention is to provide an improved mechanical trip control for presses capable of controlling the press for a single stroke operation, continuous operation and inching operation as desired.

Another object of my invention is to provide a mechanical trip control for presses which when set for single stroke operation will not repeat its cycle.

Another object of my invention is to provide a safe, completely mechanical control for presses which is certain in its operation and capable of operating for long periods of time without repair or breakdown.

A further object of my invention is to provide a mechanical trip control for presses which is simple in its operation and inexpensive to manufacture.

Other and further objects of my invention will appear from the following description:

In the accompanying drawings which form part of the instant specification and which are to be read in conjunction therewith and in which like reference numerals are used to indicate like parts in the various views:

Fig. 1 is a side elevation of a power press fitted with a mechanical trip control according to one embodiment of my invention.

2

Fig. 2 is a front elevation of a portion of the press shown in Fig. 1 drawn on an enlarged scale with parts broken away showing the mechanical trip control shown in Fig. 1.

5 Fig. 3 is an elevation viewed along the line 3—3 of Fig. 2 showing the position of parts when the press is stopped and in idle position.

10 Fig. 4 is a view similar to Fig. 3 showing the parts with the control adjusted for a single stroke operation with the foot pedal in operating position.

15 Fig. 5 is a view similar to Fig. 3 showing the parts in the position they occupy at the instant after the control has operated to stop the press with single stroke setting.

Fig. 6 is a view similar to Fig. 3 with the control set for continuous operation showing the position of parts during the operation of the press.

20 Fig. 7 is a view similar to Fig. 3 with the controls set for continuous operation showing the position of parts during the stopping of the press.

Fig. 8 is a view similar to Fig. 3 showing the position of parts during the inching of the press.

25 Fig. 9 is a front elevation of the lower part of the press shown in Fig. 1 drawn on a smaller scale showing the control foot pedal and pedal latch.

30 In general my invention contemplates the provision of a control system operating through the control of the valve governing the compressed air supply to the clutch and brake assembly of the press. In power presses it is customary to employ a continuously running flywheel adapted to be clutched to the operating train of the press or to be unclutched therefrom with the simultaneous setting of the brake.

35 In my control system I provide a linkage including a coupling member and a latching member together with timed means operated by the movement of a press part, for releasing the latch under predetermined conditions. Means are provided to set the control for continuous operation or for single stroke operation. With the single stroke setting the latch will be released, irrespective of the position of the foot pedal, at a predetermined point in the cycle of operations.

40 With the continuous setting of the controls, the press will run continuously as long as the foot pedal is depressed. Upon release of the foot pedal, the cycle will be completed and the press will stop at a predetermined point in the cycle of operation. With the inching control the latch is not permitted to perform its function. The valve will open whenever the inching lever is operated and will immediately stop when it is released, thus 45 permitting the press to be moved to any part of

its cycle. In the case of the single stroke operation and the continuous operation, the press will always stop at a predetermined point in its cycle after completing it and will not repeat irrespective of any movement of the pedal until after the cycle has been completed. The construction is completely mechanical and all of the parts are sturdy, sure of operation and inexpensive to build.

More particularly, referring now to the drawings, a press indicated generally by the reference numeral 10 may be of any desired type, style or capacity. Mounted on a side wall 12 of the frame of the press, I provide a control valve 14 adapted to be operated by a control lever 16 to govern the passage of compressed air through pipe 18 to the clutch and brake operating assembly. It is to be understood that when the valve is opened, the compressed air will cause the motor 20 to drive the press train by operating the clutch and releasing the brake.

On the other hand, when the valve 14 is closed, the springs of the clutch and brake assembly will operate to set the brake and release the clutch.

It is to be understood that I have shown my control is applied to operate a compressed air valve operating lever for purposes of illustration only and that my control is adapted to be used with any control member known to the art, such as a switch in the case of an electrically or magnetically operated clutch.

As shown in Fig. 1, the valve is in closed position and held in this position by means of spring 22 acting against bushing 24 carried by the operating lever 16 and reacting against stationary bracket 26 carried by the press frame. An operating rod 28 must move in the direction of the arrow to rotate the valve operating lever 16 in a clockwise direction against the action of spring 22 in order to open the valve.

The rod 28 is moved by actuating lever 30 of a control assembly indicated generally by the reference numeral 32 shown in greater detail in Figs. 2 to 8 inclusive. The assembly, in turn, is operated through a connecting rod 34 which is urged upwardly by the action of spring 36 acting through a collar 38 secured to the rod 34 and reacting against a flange 40 carried by a connecting assembly indicated generally by the reference numeral 42 and shown in greater detail in Figs. 2 to 8 inclusive. A connecting rod 44 is connected at its upper end by the assembly 42 to the rod 34 and at its lower end by the coupling member 46 to a foot lever 48 which is fulcrumed at its outer end around pin 50 and is provided at its opposite end with a foot plate 52 adapted to be depressed by the operator of the press. The upper dotted line position of the lever 48 shows the position of parts when the press is at rest. The lower dotted line position of the same foot lever 48 shows the position it occupies when the press is started. Upon the depression of the foot pedal, the rod 44 will move downwardly pulling rod 34 downwardly against the action of spring 36 to pivot the actuating lever 30 in a counterclockwise direction to move rod 28 upwardly against the action of spring 22 as will be described more fully hereinafter.

The control assembly 32 is provided with a trip lever 54 adapted to coat with a cam 55 which is rotated by shaft 56 of the press actuating train. An inclining lever 58 is adapted to be operated by hand to pull rod 34 downwardly through a predetermined distance as will be described more fully hereinafter.

Referring now to Fig. 2, I secure a plate 60 to the shaft 56 for rotation therewith. Adjustably

mounted upon plate 60 by means of bolts 62 I secure the cam 55. The cam is provided with a pair of slots 64 adapted to provide angular adjustment of the cam in order to permit the synchronism of the control mechanism with the operation of the press. The control assembly, which is indicated generally by reference numeral 32 in Fig. 1, comprises a pair of plates 66 and 68 between which are mounted a stationary pivoted pawl 70 and a reciprocating pivoted pawl 72, as well as the trip lever 54 and the actuating lever 30, together with pawl biasing means 74 and 76. The reciprocating pivoted pawl 72 is an impelling member adapted when pulled downwardly to rotate the actuating lever 30. The base plate 66 of the assembly is secured to the press frame 12 by means of bolts 78 and 80. A pivot pin 82 is carried by the base plate 66 around which I pivotally connect the stationary pivoted pawl 70. The upper end of connecting rod 34 terminates in a strap 84 which coats with the lower bifurcated end 86 of reciprocable pawl or impelling member 72, being pivotally connected thereto by means of pin 88. The impelling member 72 is provided with a slot 90 through which the pin 82 passes and around which the pawl 72 pivots. The stationary pawl 70 is urged to rotate in a clockwise direction as viewed in Fig. 3 by means of a spring 92 which is housed in the member 74 and acts against bracket 94 secured to the base plate 66 by means of screws 96. The spring 92 is lodged about a pin 98 carried by the bracket 94. The biasing member 76 is similar in construction to the biasing member 74 and urges the reciprocable pivoted pawl 72 to rotate about its pivot pin 82 in a clockwise direction. The upper end of the stationary pawl 70 is provided with a lug 100 which extends across a portion of the reciprocable pawl 72, as can be seen by reference to Fig. 2. The construction is such that a clockwise rotation of the pawl 70 will constrain the reciprocable pawl to move in a clockwise direction. The construction, furthermore, is such that when the reciprocable pawl moves in a counterclockwise direction the stationary pawl will be forced to move in a counterclockwise direction.

A pair of posts 102 and 104 are provided for the reception of screws 106 and 108 to secure the cover plate 68 to the control assembly. A pivot pin 110 is provided for the fulcrum of a trip lever 54. A follower roller 112 is pivotally secured to the upper end of the trip lever 54 by means of pin 114. The follower roller 112 is adapted to coat with cam 55.

The upper end of reciprocable pawl 72 is bored to receive a shaft 116. Secured to the outer end of the shaft or formed integral therewith, I provide a bearing block 118. The upper end of the reciprocable pawl 72 is provided with a reentrant portion 120 in which the block 118 is adapted to seat when it is turned through a 90° angle from the position shown in Figs. 3, 4 and 5, as can be seen by reference to Figs. 6 to 8 inclusive in which the block is shown in the seated position. Secured to the end of shaft 116 I provide a setting handle 122 which is pinned to the shaft 116 by means of pin 124. A spring 126 biases the shaft 116 to move to the left as viewed in Fig. 3.

The position of bearing block 118 can be adjusted to form an extension of the surface formed by the right hand side of the reciprocable pawl 72. By rotating the shaft 116 through 90°, the bearing block 118 may be moved to a position in which it is housed in the reentrant portion 120. In this position, when the reciprocable pawl

is depressed, the trip lever 54 will rest in a position angularly clockwise of that it occupies when the bearing block 118 is extended. This can be seen by reference to Figs. 6 and 8. The clockwise rotation of the trip lever 54 is sufficient to clear all operating contact of the cam follower 112 from the cam 55.

The connecting assembly 42 comprises the plate 130 secured to the press frame by means of bolts 132 and 134. The plate is provided with a flange 40 against which the lower end of spring 36 is adapted to seat. Pivoted about a pin 136, I provide a plate 138. The lower end of rod 44 is connected to the plate 138 by means of member 140 and pin 142. The upper end of rod 44 is connected to the plate 138 by means of member 144 and pin 146. The lower end of rod 44 is connected by coupling member 46 and pin 146 to the foot lever 48.

Referring now to Fig. 9, a pivoted locking member 148 is pivotally secured to the frame of the press by bolt 150. The locking lever 148 is provided with a weight 152 which normally pivots the locking lever to position shown in Fig. 9, that is, the unlocked position. A shoulder 154 is formed adjacent the lower end of the lever 148 adapted to coact with the foot pedal 52 as shown by the dotted lines in Fig. 9, to hold the foot lever in depressed position for continuous running.

Referring again to Figs. 2 to 8 inclusive, the inching lever 58 is pivoted about pin 136 and is adapted to contact a member 141 carried by pin 142 as can readily be seen by reference to Fig. 2. A stop 156 is carried by the plate 130 to limit the lower position to which the inching lever can be moved. The inching lever is shown against the stop in Fig. 8. The position of the stop is such as to limit the motion of the reciprocable pawl downwardly to prevent the latching of the actuating lever 30 by the stationary pawl 70.

In operation, referring now to Fig. 3, in which the parts are shown in idle position with the press stopped, the bearing block 118 has been adjusted to the single stroke position, the valve 14 is closed, the actuating lever 30 being in the position it occupies when the valve is closed. The toe of the actuating lever 30 is engaged with the projection of the reciprocable pawl 72. The foot pedal is in raised position being urged upwardly by the action of spring 36 acting through connecting plate 138 and rod 44.

Let us assume it is now desired to operate the press for a single stroke. The foot lever 48 is rotated in a counterclockwise direction by stepping upon foot pedal 52, thus pulling the rod 44 downwardly and rotating the connecting plate 138 in a counterclockwise direction. This pulls rod 34 downwardly against the action of spring 36, pulling the reciprocable pawl 72 downwardly. Since the pawl 72 is engaged with the toe of actuating lever 30, it will rotate this lever in a counterclockwise direction, pulling the rod 28 upwardly against the action of spring 22 and rotating the valve operating lever 16 in a clockwise direction to open the valve. The stroke of the movement of the pawl 72 is such that it carries the toe of the actuating lever 30 downwardly past the upper portion of latching pawl 70 camming it to rotate in a counterclockwise direction around pivot pin 82 against the action of spring 92 exerted through pawl biasing member 74 and underneath the projection at the upper end of latching pawl 70 to hold the actuating lever 30 in the position shown in Fig. 4. The valve being open permits compressed air to operate the clutch causing the press

to run. It will be observed that if the foot pressure upon pedal 52 is released, the reciprocable pawl 72 will again move upwardly to the position shown in Fig. 3. The lower toe of the trip lever 54, it will be noted, contacts with the pawl itself as shown in Fig. 3 or the bearing block 118 as shown in Fig. 4 when the bearing block is set for the single stroke position, and the foot pedal is held depressed.

As the press runs, it will rotate shaft 56 in a counterclockwise direction carrying the cam 60 around until it reaches the position shown in Fig. 5, in which the parts are shown with the foot pedal depressed but with the bearing plate 118 set in single stroke position. The cam 55 has rotated the trip lever 54 in a clockwise direction so that its toe acting against bearing plate 118 pivots the reciprocable pawl 72 around pin 82 in a counterclockwise direction. The reciprocable pawl 72 in this movement engages the lug 100 carried by the latching pawl 70 and rotates this pawl in a counterclockwise direction, thus freeing the toe of actuating lever 30 and permitting the spring 22 to move rod 28 downwardly to rotate the valve operating lever 16 in a counterclockwise direction to close the valve 14. It will be observed that it is immaterial whether or not the foot pedal 52 is held in depressed position or not. The press will always stop after completing one stroke. The trip lever 54 acts against bearing block 118 when the foot pedal is depressed and the trip lever 54 acts against the reciprocable pawl itself when the foot pedal is raised.

For continuous operation, the bearing block 118 is housed as shown in Figs. 6 to 8 inclusive. Referring now to Fig. 6, in which the parts are shown with the press running and the foot pedal held downwardly by means of the latch 148, it will be observed that the actuating lever 30 has its toe latched in running position by the pawl 70. The trip lever 54 is clear of the cam 55 so that rotation of the press will not actuate the trip lever 54 to cause the reciprocable pawl 72 to be rotated in a counterclockwise direction. The housing of the bearing block 118 removes the surface through which the lower toe of trip lever 54 acts. The press will run continuously with the parts in the position shown in Fig. 6.

Let us now assume that it is desired to stop the press with the bearing block 118 housed, that is, in the continuously running position. This is accomplished by releasing the foot lever latch 148 so that the pedal will move to its upper position as shown in Fig. 7. This permits the reciprocable pawl 72 to move upwardly to the position shown in Fig. 7. The upward motion of the reciprocable pawl cams the trip lever 54 to move in a counterclockwise direction raising the roller 112 into the path of the cam 55. When the cam moves around to its predetermined position, it will rotate the trip lever in a clockwise direction around its pivot pin 110 forcing the reciprocable lever to rotate around its pivot pin 82 in a counterclockwise direction and carrying with it the latching pawl 70 through the lug 100 formed thereon, thus releasing the toe of the actuating lever 30. The press will stop at its predetermined position in accordance with the motion of the cam.

When it is desired to inch the press and move it to any desired point in its cycle, the inching lever is operated. Rotation of the inching lever in a counterclockwise direction around its pivot pin 136 will move the reciprocable pawl 72 downwardly carrying with it the toe of the actuating

lever 30 causing it to rotate in a counterclockwise direction around its pivot pin 31 to lift the connecting rod 28 and thus operate the valve operating lever 16. It will be observed, however, that the inching lever 58 has a predetermined limit of motion governed by the stop 155. This limit is such that the downward motion of the reciprocable pawl 72 is above that at which the toe of the actuating lever 30 would be latched downwardly by the pawl 70. The result is that when the inching lever is released the valve immediately closes. The arrangement is such that it is impossible to cause the press to run except when the inching lever is depressed. It will not complete a cycle unless the inching lever is held downwardly during the entire cycle. As soon as the inching lever is released, since the latching pawl 70 is ineffective, the valve will close under the influence of spring 22 which moves the valve operating lever 16 to rotate in a counterclockwise direction thus closing the valve.

It will be seen that I have accomplished the objects of my invention. I have provided an improved mechanical trip control for presses capable of controlling the press for a single stroke operation, continuous operation and inching operation as desired. My control is completely mechanical and is certain in its operation and capable of operating for long periods of time without breakdown necessitating repairs. My mechanical trip control is simple in its operation and inexpensive to manufacture. The parts are sturdy and visible. My press can be accurately adjusted to stop the cycle within predetermined limits determined by the setting of the cam 55.

I have described my trip control with respect to presses for purposes of illustration. It is to be understood that my trip control may be applied to any machine driven by a primary mover through the agency of a fly wheel and clutch such as machine tools, printing presses, hoisting equipment and the like.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A control assembly for power presses including, in combination, an actuating lever for controlling the press, an impelling member having operative engagement with said actuating lever, a detent adapted to hold said actuating lever in press operating position, a trip lever adapted to release said detent, means coupling said detent and said impelling member whereby movement of said impelling member in a predetermined direction will drive the detent to actuating lever releasing position, said impelling member being formed with a surface adapted to engage said trip lever when the impelling member is in press stopping position, adjustable means carried by said impelling member adapted selectively to be moved to a position engaging the trip lever when said impelling member is in press running position whereby the control assembly may be adjusted for single cycle operation or for continuous operation and means responsive to

the movement of a press part for actuating said trip lever at a predetermined point of the press operation cycle.

2. In a control assembly for power presses, an actuating lever for controlling the press, a manually operable reciprocable member having engagement with said actuating lever and adapted to move it to press running position, a detent adapted to engage said actuating lever to hold it in press running position, a detent trip lever, means responsive to the movement of a press part for driving said trip lever, means carried by said reciprocable member coacting with said trip lever and means providing an operable connection between said reciprocable member and said detent to release said actuating lever in response to motion of said trip lever.

3. A control assembly for power presses including in combination a control member adapted to be actuated to control the operation of a press, an actuating lever for operating the control member, an impelling member having operative engagement with the actuating lever, a detent adapted to hold the actuating lever at press operating position, a trip lever adapted to release the detent, means coupling the trip lever and the detent, a cam for driving the trip lever, means for mounting the cam for movement as a function of the movement of a press part, manually operable means for moving the impelling member to start the operation of the press, said means coupling the trip lever and the detent including interengageable means carried by the impelling member and the detent and an adjustable surface carried by the impelling member adapted to contact the trip lever when the impelling member is in a position moving the actuating lever to press running position.

4. A control assembly for power presses including in combination a control member adapted to be actuated to control the operation of a press, an actuating lever for operating the control member, an impelling member having operative engagement with the actuating lever, a detent adapted to hold the actuating lever at press operating position, a trip lever adapted to release the detent, means coupling the trip lever and the detent, a cam for driving the trip lever, means for mounting the cam for movement as a function of the movement of a press part, manually operable means for moving the impelling member to start the operation of the press, said means coupling the trip lever and the detent including interengageable means carried by the impelling member and the detent and an adjustable surface carried by the impelling member adapted to contact the trip lever when the impelling member is in a position moving the actuating lever to press running position, the adjustable surface comprising a bearing block, means for supporting the bearing block adjacent the upper end of the impelling member, said upper end being formed with a recess and means for housing the bearing block in the recess to set the control for continuous operation.

5. A control assembly for power presses including in combination a control member adapted to be actuated to control the operation of a press, an actuating lever for operating the control member, an impelling member having operative engagement with the actuating lever, a detent adapted to hold the actuating lever at press operating position, a trip lever adapted to release the detent, means coupling the trip lever and the detent, a cam for driving the trip lever, means

for mounting the cam for movement as a function of the movement of a press part and manually operable means for moving the impelling member to start the operation of the press, the manually operable means for moving the impelling member comprising a foot lever, a second manually operable means for moving the impelling member and a stop for limiting the motion of the second manually operable means to render the detent ineffective to latch said actuating lever upon the 10 operation of the impelling member.
